UNITED STATES PATENT OFFICE

125,093

DESIGN FOR A COMBINED CALENDAR,
THERMOMETER, AND HUMIDITY INDICATORWilliam B. Petzold, Pittsfield, Mass., assignor to
General Electric Company, a corporation of
New York

Application November 27, 1940, Serial No. 96,883

Term of patent 14 years

To all whom it may concern:

Be it known that I, William B. Petzold, a citizen of the United States, residing at Pittsfield, in the county of Berkshire, Commonwealth of Massachusetts, have invented a new, original, and ornamental Design for a Combined Calendar, Thermometer, and Humidity Indicator, of which the following is a specification, reference being had to the accompanying drawing, forming part thereof.

In said drawing:

Figure 1 is a perspective view of a combined calendar, thermometer and humidity indicator showing my new design.

Figure 2 is a rear view.

The opposite side to that shown in Fig. 1 presents the same appearance as that of the side shown. The printed matter shown in Fig. 1 of the drawing is merely representative in character.

I claim:

The ornamental design for a combined calendar, thermometer, and humidity indicator, as shown and described.

WILLIAM B. PETZOLD.
